[57] CLAIM

We claim the ornamental design for a dual aquaplaning craft, as shown and described.

DESCRIPTION

FIG. 1 is a top perspective view of a dual aquaplaning craft showing our new design, the broken lines are for illustrative purposes only;

FIG. 2 is a top plan view thereof;

FIG. 3 is a left side elevational view thereof, the right side elevational view being a mirror image of that shown;

FIG. 4 is a bottom plan view thereof;

FIG. 5 is a front elevational view thereof; and,

FIG. 6 is a rear elevational view thereof.
